ATTORNEY.

UNITED STATES PATENT OFFICE.

JEREMY BARTLETT, OF COLLINS, NEW YORK, ASSIGNOR OF SEVEN-TWELFTHS TO WILLIAM W. HENRY, OF LITTLE VALLEY, AND RODNEY R. CROWLEY, OF RANDOLPH, NEW YORK.

MAIL-BAG FASTENER.

SPECIFICATION forming part of Letters Patent No. 585,174, dated June 29, 1897.

Application filed January 2, 1897. Serial No. 617,752. (No model.)

To all whom it may concern:

Be it known that I, JEREMY BARTLETT, a citizen of the United States, residing at Collins, in the county of Erie, State of New York, 5 have invented certain new and useful Improvements in Mail-Bag Fasteners; and I hereby declare the following to be a full, clear, and exact description thereof, reference being had to the accompanying drawings; in 10 which—

Figure 1 is a plan view of the top portion (back) of a mail-bag, the hasp and tag-holder in elevation and the chain and hook-fastener and staples in dotted lines, the bag being 15 shown as closed and secured. Fig. 2 is a plan view of the top portion of the mail-bag reverse (or flap) side, the flap being closed down and the staple-plates shown in dotted lines. Fig. 3 is a plan view, same side as shown in 20 Fig. 2, the flap being raised and portions of the front wall of the bag and the fold or sheath which conceals the fastener broken away to disclose portions of the fastener.

Like symbols refer to like parts wherever 25 they occur.

My invention relates to the construction of devices for securing the mouths of mail-pouches, and has for its object to produce an efficient, simple, light, and inexpensive fastener which can be quickly operated to secure 30 and release the flap of the mail-bag or to close and open the mouth of the bag.

To this end the main feature of my invention embraces the combination, with a series 35 of pivoted hooks, of a plurality of flexible non-extensible connections attached to said hooks on opposite sides of their pivotal points, whereby the fastening devices are operated from and secured at points on both sides of 40 their points of rotation.

There are other minor features of invention, all as will hereinafter more fully appear.

I will now proceed to describe my invention more specifically, so that others skilled in the 45 art to which it appertains may apply the same.

In the drawings, A indicates the mail-pouch, and B the flap thereof, provided with the usual or any approved form of staples b, attached thereto by the staple-plates c. The 50 alined series of staples b b are those through

which the hooks of the fastener pass, while the central leading staple h is the one which engages the hasp H.

In that portion of the wall of the bag and in the envelop or sheath a which covers and conceals the fastening devices are a series of slots b' b² for the passage of the staples b b, &c., which receive the hooks of the fastener, and opposite the hasp-staple h is a slot h', which passes through both walls of the bag 60 and through the intermediate envelop or sheath a for the passage of hasp-staple h, which projects at the back of the bag for the reception of the hasp H.

The hasp H is pivoted in a hasp-plate H', 65 firmly secured to the bag by rivets or in other suitable manner, and to the inner end of the hasp-pivot, within the bag, is secured a short lever 1.

On the inner wall of the bag, secured there- 70 to by rivets or in other suitable manner, in line with and preferably equidistant from each other and from the pivot of the hasp H, are a series of pivot-plates 2, on each of which plates is pivoted the vertical shank 3^a of a 75 hook 3, at or about mid-length of the shank, said shanks so arranged that when the hooks 3 3 are within the staples b and the bag is locked the said shanks shall stand parallel with each other and with the lever 1, attached 80 to the pivot of the hasp H.

The shanks 3^a of the hooks 3 are connected with each other and with the lever 1 by a plurality of flexible non-extensible connec- 85 tions 4 5—at least two—one on each side of the pivotal points, and preferably equidistant from said pivotal points, so that on the rotation of the lever 1 power shall be applied simultaneously to all the hook-shanks in oppo- 90 site directions and on opposite sides of the pivotal points thereof, and thus insure easy and accurate working of the devices. Such connection of the hook-shanks on both sides of the point of rotation forms, when the bag is locked, a parallelogram or plurality of 95 parallelograms, of which the hook-shanks constitute the rigid ends and the two chains, one on each side of the pivot-point of said shanks, constitute the two non-extensible sides, which resists any springing or lateral 100

movement of the hook-shanks that might occur or be caused in case of a single chain or flexible connection between the hook-shanks, and thus the plurality of chains on opposite sides of the pivots of the hook-shanks prevents the independent manipulation of any hook or its removal from the staple by accident or design, and as the hooks 3 are curved or arc-shaped to facilitate their entering the staples 10 b the connection 5, which is between the curve of the hook and the pivot, will act as a keeper to the hook and afford additional security to the fastener.

The preferred form of the flexible connections 15 between the hook-shanks 3^a and the lever 1 is that of a chain composed of alternate flat or plate links 6, with which the lever 1 and hook-shanks 3^a are pivotally connected, as at 6^a, and intermediate rod-links 20 7, which facilitate the folding of the bag without permitting the displacement of the hooks.

The hasp H may be provided with inturned flanges, which not only render the hasp more 25 rigid, but constitute a holder T for the reception of a tag or card, and said hasp is preferably arranged to stand and move parallel with lever 1 and hook-shanks 3^a, so that the 30 position of the hasp at all times indicates the position of the hooks 3 or fastener.

The fastening devices when secured within the mouth of the bag are covered and concealed by a sheath or fold a of leather, which may be riveted at intervals to the wall of the 35 bag to prevent any tampering with the fastener.

The fastener, being constructed substantially as hereinbefore specified, will be operated as follows: The bag being locked and in 40 the position indicated in Fig. 1 of the drawings, the hasp H is raised from the staple h and rotated to the right, as indicated by the arrow, Fig. 1, whereupon the lever 1 and hook-shanks 3^a will rotate to the right, thus 45 simultaneously withdrawing all the hooks 3 from the staples b, after which the bag can be turned over and the flap raised to expose the mouth of the sack. To lock the bag, fold down the flap and place the bag on a flat surface 50 with flap underneath, whereupon the several staples will register with and enter

their respective slots, when the hasp H may be rotated from right to left to bring it back into line with hasp-staple h, which movement of the hasp will, through lever 1 and chains 45 5, be communicated simultaneously to all the hook-shanks 3^a, causing the hooks 3 to enter the staples b and secure the mouth of the bag, after which the usual padlock will be applied to secure the hasp H. 60

Having thus described my invention, what I claim, and desire to secure by Letters Patent, is—

1. In a mail-bag fastener, the combination with a series of pivoted hooks, of a plurality of flexible non-extensible connections said connections attached to each of said hooks on opposite sides of their pivotal points; substantially as and for the purposes specified. 65

2. In a mail-bag fastener, the combination 70 with a pivoted hasp, of a series of pivoted hooks, and a plurality of flexible non-extensible connections which connect the hasp and each of the hooks of said series on opposite sides of their pivotal points; substantially as 75 and for the purposes specified.

3. In a mail-bag fastener the combination of a series of pivoted hooks, and a plurality of non-extensible chain connections therefor, said connections having plate-links with 80 which each hook of the series is connected on opposite sides of the pivotal point of the hook; substantially as and for the purposes specified. 85

4. In a mail-bag fastener the combination 90 of a series of pivoted hooks, and a plurality of non-extensible chain connections therefor, each of said chain connections consisting of plate and rod links, the shanks of each hook of the series being connected with a plate-link of each of the chain connections on opposite sides of the pivotal point of the hook; substantially as and for the purposes specified. 95

In testimony whereof I affix my signature, 95 in presence of two witnesses, this 12th day of December, 1896.

JEREMY BARTLETT.
